UNITED STATES PATENT OFFICE.

JAMES B. MILLER, OF ROCHESTER, NEW YORK, ASSIGNEE, BY MESNE ASSIGNMENTS,
TO THE FI-BO-PAK COMPANY, OF ROCHESTER, NEW YORK, A CORPORATION OF NEW
YORK.

BASKET AND HANDLE THEREFOR.

1,241,542.

Specification of Letters Patent. Patented Oct. 2, 1917.

Application filed March 22, 1915, Serial No. 16,194. Renewed July 28, 1917. Serial No. 183,382.

To all whom it may concern:

Be it known that I, JAMES B. MILLER, a citizen of the United States of America, and a resident of Rochester, New York, have 5 invented certain new and useful Improvements in Baskets and Handles Therefor, of which the following is a specification.

The object of this invention is to provide a construction of fruit baskets whereby the 10 cover thereof is held in place without necessitating special parts, and to facilitate the attachment of a handle thereto, as is particularly desirable in the smaller grades of baskets, such as those in which grapes are 15 commonly shipped.

For these purposes it comprises a novel construction of a desirable handle, which may be readily put in place, and which, when in place, provides means of securing 20 and holding down the cover, and of permitting the cover to distend the sides of the container, as is desirable in this class of ware, both in giving additional strength to the container, and in giving a more attractive appearance to the basket when the cover 25 is removed. It further consists in the construction, combination and arrangement of the several parts of which it is composed, as will be hereinafter more fully described 30 and claimed.

Referring to the accompanying drawings in which corresponding parts are designated by corresponding marks of reference,—

Figure 1 is a perspective view of a handle 35 constructed in accordance with this invention.

Fig. 2 is a vertical section through a fruit basket having my invention applied thereto.

The receptacle A as illustrated in the 40 drawings is of the general type now in use, and is preferably made of fiber board.

The handle B is formed of a single piece of wire comprising a central portion or carrying section b, and downwardly extending arms b', terminating in convolutions formed 45 as follows, the description being that of the convolution on one arm, it being of course understood that the other arm is likewise formed. The wire at the lower end of the part b' is bent outwardly at b² forming a shoulder, and then downwardly as at b³, substantially parallel with the portions b'. It is then bent inwardly and upwardly as at b⁴, parallel to the portion b³, and then 55 inwardly and downwardly as at b⁵, parallel

to the portions b³ and b⁴, and substantially in the line of the extension b', the lower part of b⁵ terminating in an outwardly bent portion b⁶ located below and adjacent the bend connecting the parts b³ and b⁴. The opening 60 between the parallel portions b⁴ and b⁵ should be of such width as to permit them to engage the outer and inner walls of the sides of the basket, and the loop connecting the parallel portions b⁴ and b⁵ should be 65 formed adjacent the end b⁶. Two convolutions are thus formed in each of the downwardly extending arms, the outer convolution being formed by the portion b³ and b⁴, and the inner convolution by the portions b⁴ 70 and b⁵, both of these convolutions being connected by the loop formed between the portions b⁴ and b⁵ which straddle the walls of the basket. By this construction, the end b⁶ will be held permanently within the side 75 walls of the basket, irrespective of its position, or of any lateral movement of the walls of the basket caused by the handle, or the cover as hereinafter described.

Such a handle is secured to the receptacle 80 by inserting the upper edges of the opposite sides of the receptacle between the portions b⁴ and b⁵ of the convolutions of the handle until such edges abut against the loop formed between the portions b⁴ and b⁵. 85 The bent ends b⁶ of the convolutions can be now passed outwardly through the sides of the receptacle, which may be apertured as at a' for this purpose. In so inserting the handle, the slight flexibility possessed by the 90 walls of the receptacle due to their construction of fiber-board, permits the necessary bending of such walls to permit the slipping of the handle in place, while, upon the handle slipping into place, the sides of the 95 container will be supported by the portions b⁴ and b⁵ of the handle convolutions which are on opposite sides thereof, and thus the hook be prevented from slipping out.

In applying a cover C, the edges thereof 100 are slipped under the bend b⁶ of the handle, and is thus held down upon the top of the basket. By preference, the cover itself is of such width that when the basket has been filled, and the cover forced into place, it 105 will, by pressing upon the upper part of the portions b⁶ of the handle, distend the latter, and the side walls of the receptacle, thus permitting the basket to be filled slightly heaping without crushing the fruit upon the

cover going into place, while upon the cover being removed the spring of the basket and of the handle, will again draw in the sides, (as shown in dotted lines Fig. 2) and thus 5 tend to raise the level of the top of the fruit to destroy any settlement which may have taken place in the contents of the basket during transportation.

Having thus described the invention what 10 I claim, and desire to secure by Letters Patent is:—

1. The combination with a basket and a cover therefor, of a handle for the basket, the handle comprising downwardly extending arms having end parts, each terminating in an outwardly extending portion projecting outwardly through the walls of the basket, the end parts each having above the outwardly extending portion thereon three 15 parallel portions, two of which straddle the walls of the basket, and the third of which is connected to one of the downwardly extending arms by a shoulder located above and retaining the cover in place.
2. A handle for a basket comprising a handle portion and downwardly extending arms, each of which terminates in an outwardly extending end part, each downwardly extending arm having above such 20 25

end part three parallel portions, two of 30 which are adapted to straddle the walls of the basket, and the third of which is connected to the two parallel portions which are adapted to straddle the basket by a shoulder extending outwardly therefrom and located adjacent to said outwardly extending end part, and a shoulder connecting the handle portion and end parts. 35

3. A handle for a basket comprising a carrying section substantially parallel with 40 the bottom of said basket, and downwardly extending arms attached to each end of said carrying section, said downwardly extending arms each being formed with two convolutions and having an inner projecting 45 shoulder above the said convolutions, and an outer projecting end part below the said convolutions, the inner one of the said two convolutions being adapted to overlap the wall of the said basket, and the said outer projecting end part adapted to pass through the wall of the said basket. 50

In testimony whereof I hereunto affix my signature in the presence of two witnesses.

JAMES B. MILLER.
